(57) **CLAIM**

The ornamental design for a dreadlocks threading tool, as shown and described.

DESCRIPTION

FIG. 1 is a Top Front Perspective view of a dreadlocks threading tool showing my new design; FIG. 2 is a Front elevation view thereof; FIG. 3 is a Rear elevation view thereof; FIG. 4 is a Top plan view thereof; FIG. 5 is a Bottom plan view thereof; FIG. 6 is a Right elevation view thereof, with the Left elevation view being a mirror image thereof; and, FIG. 7 is a perspective view of the dreadlocks threading tool; shown in an environment of use.

The broken lines in FIG. 7, illustrate environmental subject matter only and form no part of the claimed design.
